UNITED STATES PATENT OFFICE.

FREDERICK LACHLAN MCKINNON, OF ABERDEEN, SCOTLAND.

GRINDING OR PULPING MACHINE.

1,099,187.

Specification of Letters Patent.

Patented June 9, 1914.

Application filed January 7, 1914. Serial No. 810,780.

To all whom it may concern:

Be it known that I, FREDERICK LACHLAN MCKINNON, a subject of the King of the United Kingdom of Great Britain and Ireland, and resident of Aberdeen, Scotland, have invented a certain new and useful Improvement in Grinding or Pulping Machines, of which the following is a specification.

10 This invention relates to grinding or pulping machines applicable for treating coffee and the like and has for its primary object to provide an improved construction of adjustable breast for such machines, for 15 separating the pulp from the berries of coffee for instance.

20 In the accompanying drawings Figure 1 is an elevation of an adjustable breast embodying the invention; Fig. 2 is a vertical section on the line A, B Fig. 1.

25 Referring to the drawings, the doors or gutters 1, 1 are formed integral with the solid casting of the breast 2, the edges of the doors or gutters at the bottom 3 and sides 4, 4 being separated from the casting by saw cuts. By this arrangement a spring 30 door or gutter is provided, there being sufficient elasticity in the cast iron of which the breast is made to permit of the necessary adjustment of the door or gutter. The doors may be adjusted by means of hand-wheels 5 carried by a cross bar 11 secured to the breast 2, and in screw-threaded engagement with studs 12 fitted to the doors 35 1. The hand-wheels 5 are provided with locking wing nuts 10.

To prevent the doors from being moved too far from central position while being adjusted and thus being caused to snap off, a locking arrangement is provided to limit 40 the movement of each door. The locking arrangement consists of a plate 6 fitted on the breast 2 over, and spaced apart from, the door 1, said plate 6 having a central perforation 7 through which is passed a pin 45 8 mounted on the door 1. The pin head abutting on the outer surface of said plate 6 limits the inward movement of the door, the outward movement being limited by the door 1 abutting on the inner surface of said 50 plate 6.

What I claim is:—

1. A breast for a grinding or pulping machine comprising a resilient body portion having an integral door partially separated 55 from said body portion.

2. A breast for a grinding or pulping machine comprising a resilient casting having an integral door partially separated from the body of said casting, in combination 60 with means for adjusting said door and means for limiting the movement of said door in either direction.

In testimony whereof I have signed my name to this specification in the presence of 65 two subscribing witnesses.

FREDERICK LACHLAN MCKINNON.
